UNITED STATES PATENT OFFICE.

JOHN E. MITCHELL, OF ST. LOUIS, MISSOURI.

COTTON EXTRACTING AND CLEANING MACHINE.

1,030,913.

Specification of Letters Patent.

Patented July 2, 1912.

Application filed November 18, 1911. Serial No. 661,099.

To all whom it may concern:

Be it known that I, JOHN E. MITCHELL, a citizen of the United States, residing in the city of St. Louis and State of Missouri, have 5 invented new and useful Improvements in Cotton Extracting and Cleaning Machines, of which the following is a specification.

This invention relates to certain new and useful improvements in cotton-extracting 10 machines, and is designed particularly to improve the type of machine heretofore invented by me embodied in an application for patent, filed July 5th, 1911, Serial Number 636,828. In common with the machine 15 embodied in the application above named, the present machine may be used either in conjunction with a gin to clean said cotton and better prepare it for the ginning operation, or it may be used for extracting cotton 20 from bolls, and especially from closed bolls. In its use in either connection, I have found that the successful operation of the machine depends to a very large extent on the regulation of the feed of the hulls and cotton 25 past the saw cylinder. In my pending application, above named, I have shown a single hull board, in the form of a grate bar, adapted to be adjusted toward and from the saw cylinder to regulate the size of the space 30 through which the hulls pass to the discharge. It is exceedingly difficult, however, to accomplish the best results with a single hull board, for the reason that if the space between the hull board and the saw cylinder 35 is made sufficiently large to permit a free passage of the hulls past the saw cylinder, which is necessary to prevent choking of the machine, it inevitably follows that a great deal of cotton will be carried through 40 with the hulls without coming in contact with the saw cylinder, and hence be wasted. On the other hand, if the space be lessened 45 to prevent the waste of cotton, the restriction of the outlet will result in choking up the machine and thereby prevent its proper working.

The principal aim of the present invention is to overcome the inherent objection of a single hull board, and to this end the invention 50 comprises a pair of parallel hull boards adjustably mounted in the machine and located one above the other, and normally positioned so that the edge of the upper hull board will be at a greater distance 55 from the saw cylinder than is the edge of the lower hull board, while between the

boards there is a free clearance space to permit the escape of pieces of hull, refuse, or the like, which may be knocked outward by contact with the teeth of the saw cylinder. 60

In addition to the improvement in the hull board, as above outlined, the present invention also embodies an improvement in the feeding devices, which I have demonstrated in practice presents the mixed cotton 65 and hulls in the best condition for subsequent action by the saw cylinder, and likewise feeds the material uniformly, while at the same time crushing any pods fed into the machine. 70

By the special construction of parts hereinafter described and claimed, as well as by the general combination, arrangement and coöperation of the elements entering into the machine as a whole, I have devised a 75 machine which will operate in a continuous and highly efficient manner to separate impurities from said cotton, or with equal efficiency to crush bolls, open or closed, and separate the cotton therefrom from the hulls. 80

In the accompanying drawing, the view is a cross section of a machine constructed according to my invention, a small portion thereof being shown in elevation to illustrate the means for adjusting the hull 85 boards.

Referring now to the drawing, 1 indicates the casing of the machine, which is provided with a hopper 2, in the lower part of which is mounted, on a shaft 3, a revolving crusher 90 and feeder 4, which, as shown, is a cylinder having mounted on its periphery a series of pins 5. Supported at its upper end on the wall of the hopper, and at its lower end on an angle-iron 6, which extends between the 95 sides of the machine, I provide a wire screen 7 which is curved at its lower end to conform somewhat to the curvature of the cylinder 4, the purpose of this screen being to effect an initial separation of some of the dirt, 100 refuse, and the like, from the cotton, which material may be small enough to pass through the meshes of the screen 7. Such refuse material passes through the screen and falls to the bottom of the machine on to an incline 8, whence it passes out through an opening 9 in the rear side of the machine. Above the crushing cylinder 4 are mounted two similar rollers 10, the shafts 11 of which are supported in bearings in opposite sides 110 of the hopper 2, said rollers being designed to be driven in opposite directions, or

toward each other, and being provided with longitudinal blades, or the like, for engaging and feeding the cotton. I have not considered it necessary to shew the belts and gearing for rotating the various members referred to, and others later to be referred to, particularly as I lay no claim to the special arrangement of the feeding and crushing cylinders, except in so far as they enter into 5 the general combination of the machine. I will state, however, that in practice the crushing cylinder 4 is rotated at a relatively high rate of speed as compared with the feeding rolls 10, and that by so speeding up 10 the crushing cylinder I not only secure the proper feed of the cotton, but likewise effect the crushing of bolls fed into the machine by impact therewith of the blades 5, which likewise act to throw the broken hulls and 15 refuse material with considerable force against the screen 7 and effect an initial separation of refuse, which is of very material advantage. 13 indicates a saw cylinder mounted on a shaft 14, and 15 a rotary pod- 20 expeller, mounted on a shaft 16, the latter rotating in the same direction as the saw cylinder and operating to knock back any pieces of hull, or the like, carried up by the saws. 17 indicates a doffer-brush, mounted 25 on a shaft 18, and operating to remove cotton from the saw cylinder. These parts are embodied in my pending application, their function is fully described therein, and they need not be referred to herein more in detail. 30 Located above the pod-expeller 15 is a hinged board 19 extending parallel therewith throughout the length of the pod-expeller, and normally resting on a stop 20. This board acts in the nature of a guard to 35 prevent refuse material being carried around by the pod-expeller and delivered to the forward side of the saw cylinder, where it would be thrown into the cotton by the doffer-brush. This guard may be readily 40 swung upward to permit access to the interior of the machine, and will also readily yield to permit the passage of any object carried up by the pod-expeller too large to pass between the latter and the said guard. 45 It will be understood, of course, that the shafts 14, 16 and 18 are suitably journaled in the walls of the machine, and that proper driving means are employed for rotating them in the respective directions it is desired 50 they should turn.

Situated below the crushing cylinder 4, and to one side of the saw cylinder, are the hull boards, of which 21 indicates the upper board and 22 the lower. These two hull 55 boards are preferably connected in rigid parallel relation by means of a bracket-arm 23 having opposite ends bolted to the respective hull boards at each end of the latter, only one of said bracket-arms being shown, 60 and said brackets being provided with open-

ings for the reception of a rod 24 on which the hull boards, as a whole, are secured. The rod 24 is journaled at opposite ends in the sides of the casing, and is located nearer to the hull board 21 than to the hull board 70 22, as shown, so that the latter, having a larger arc of movement, may be adjusted toward or from the saw cylinder without materially affecting the distance therefrom of the edge of the upper board 21. Secured 75 on one end of the rod 24 is an arm 25, having a curved slot 26, through which slot extends a screw-threaded pin 27 mounted on the outer wall of the casing, and on which is screwed a jam-nut 28. By loosening this 80 nut the hull boards may be turned on the rod 24 as a pivot, and to adjust the distance, particularly of the lower hull board, from the cylinder, after which the jam-nut is screwed home to lock the hull boards in the 85 adjusted position.

It will be seen that in the adjustment shown in the drawing the space 29 between the lower edge of the hull board 21 and the saw cylinder 13 is considerably greater than 90 the space 30 between the lower edge of the hull board 22 and the saw cylinder. In my pending application referred to, I have set forth the advantage of having a free, unoccupied space adjacent to the saw cylinder to permit the agitation of the cotton and to prevent choking the machine. It will be observed that between the hull boards 21 and 22, and adjacent to the saw cylinder, there is a space 31, and this space, in a less 100 degree, has somewhat the function of the larger agitating chamber above the hull board 21. This space 31, however, is not confined by a rear wall, but a continuous opening is provided between the boards 105 from the front to the rear thereof so that pieces of hull, and the like, thrown up by the saws may pass out between the hull boards and fall from the machine through the opening 9. This latter feature, providing a means of escape for the hulls and refuse, in addition to that provided by the space between the inner edges of the hull boards and the saw cylinder, is of the greatest importance, insuring as it does the certain and rapid separation of a large part of the refuse from the cotton which could not otherwise be so separated except at the expense of a considerable waste of cotton. 110 This may be clearly understood from a comparison of the single and double hull board arrangements, and a consideration of the differences in their operation. In the case of a single hull board, if it is adjusted so as to provide a space between its lower edge 115 and the saw cylinder sufficiently narrow to prevent the escape of cotton, it would at the same time absolutely prevent the discharge of a large portion of the refuse that could not pass through the opening. If, on the 120 125 130

other hand, and as is necessary in operation, the space were made large enough to permit the escape of all the refuse, a considerable portion of cotton would be carried 5 along with it and lost. This difficulty is overcome in the use of the double hull board arrangement, in which case the upper board is adjusted to provide a space between its lower edge and the saw cylinder sufficiently 10 wide to permit the discharge of all the refuse, which carries with it some of the cotton. The lower hull board, however, is so adjusted relative to the saw cylinder that the space between its lower edge and the saw 15 cylinder is too narrow to permit the escape of the remaining cotton, and while the smaller particles of refuse, trash, etc., are readily discharged by gravity through this space, the larger particles, such as hulls, 20 bells, stones, sticks, etc., must be thrown or knocked by the saws through the space between the hull boards, and over the top of the lower hull board, or else they could not be eliminated at all, and the machine would 25 be inoperative. The width and position of the lower hull board must, therefore, be such as to permit this operation, and the space between the two hull boards must be relatively wide and of no great depth, so 30 that the hulls and refuse may be readily thrown out without having to travel or rise any considerable distance, as otherwise they would fall upon the lower hull board and slide back against the saw cylinder. To 35 this end I preferably make the lower hull board of less width than the upper hull board, with its upper edge lying in a lower plane than the lower edge of the upper hull board, and with said edge lying also in a 40 vertical plane, cutting the upper hull board, and in a horizontal plane cutting the saw cylinder. This construction affords an uninterrupted horizontal passage from the saw cylinder between the upper edge of the lower 45 hull board and the lower edge of the upper hull board. The rear edge of the lower hull board, in addition, is located at a considerable distance from the rear wall of the machine, bringing such edge relatively close to 50 the saw cylinder, so that the distance the hulls and refuse must travel when thrown upward by the saw cylinder before passing out of the rear opening of the space between the hull boards is very slight. It will be 55 understood, of course, that I do not wish to be limited, otherwise than as specified in the claims, to the precise size, arrangement or location of the lower hull board above described.

60 In operation the pods are fed into the hopper 2 and pass between the feed rolls 10, which slightly compresses the mass, and, as it were, holds the same while the bottom 65 part of the mass of cotton and bolls is knocked off by the rapidly revolving cylinder 4. As the blades 5 of this cylinder come in contact with the bolls it cracks and crushes them, throwing them with some force against the screen 7, and a part of the dirt and small pieces of hull will pass through said screen and fall out of the machine by way of the opening 9. The cotton mixed with the hulls comes in contact with the saw cylinder 13, the saws whereof engage and carry the cotton under the pod-exeller 15, the latter being located at such distance from the surface of the saw cylinder that it will knock back any pieces of hull which may be carried upward with the cotton. These pieces of hull gradually find their way by gravity to the opening 29, and to a certain extent any pieces of hull having cotton attached thereto will be carried upward again by reason of the saws engaging the cotton. As I have explained above; however, this opening 29 must be made sufficiently large to permit the free passage of the hulls past the saw cylinder, and it is found that quite an amount of cotton is carried past the saws, and if no other means were provided to reclaim it, it would pass out of the machine and be wasted. According to the present invention, however, the hulls will next fall by gravity to the space 30, which, being narrower than the space 29, will throw the hulls closer to the space 29, as they fall through. It thus occurs if any pieces of hull have cotton adhering to them the cotton will be engaged by the saws and be removed from the hull in the manner described, while other pieces of hull not containing cotton will be knocked outward by the saws through the space between the two hull boards, and fall out of the machine through the opening 9. Other pieces of hull free from cotton will, of course, fall through the opening or space 30 and slide down the inclined bottom 8 to the outside of the machine. The hull boards 21 and 22 are inclined toward the saw cylinders, and thus the tendency is for the material resting on these hull boards to fall by gravity against the saw cylinder. Thus all material delivered on to the saws until, being entirely freed from cotton, it will pass from the machine through one or the other of the ways described.

In the event the machine is used for preparing seed cotton for the gin, the same operations occur as above described, except that the cylinder 4 then acts more as a feed regulating cylinder to loosen and draw out the cotton and present it to the saw cylinders in the best condition to be acted on so that any pieces of hull, sticks, or the like, mixed therewith may be readily separated therefrom.

In conclusion it may be stated that the distance between the upper hull board and

the saw cylinder will usually approximate an inch and a half, and when the upper hull board is at this distance from the saw cylinder the edge of the lower hull board 5 will be about one inch from the saw cylinder. Both of these distances, however, may be advantageously varied within certain rather narrow limits, according to the character of the material being treated or the 10 purpose for which the machine is being used.

I claim:

1. In a machine for extracting and cleaning cotton, in combination with a rotary saw 15 cylinder, a rotary pod-expeller and a doffer-brush co-operating therewith, feeding mechanism, and a pair of superposed hull boards defining the size of two alining passages past the saw cylinder, and affording 20 between them a free clearance space so positioned that pieces of refuse may be knocked by the saws through said space and over the rear edge of the lower hull board.

2. In a machine for extracting and cleaning cotton, in combination with a rotary saw 25 cylinder, a pod-expeller and doffer-brush co-operating therewith, and a pair of superposed hull boards affording between them a free clearance space and so positioned that 30 the space between the edge of the upper hull board and the saw cylinder is greater than the space between the lower hull board and the saw cylinder, and that the upper edge of the lower hull board is in a plane no 35 higher than the plane of the lower edge of the upper hull board.

3. In a machine for extracting and cleaning cotton, in combination with a rotary saw cylinder, a pod-expeller and doffer-brush co- 40 operating therewith, and a pair of hull boards located one above the other, the rear edge of the lower hull board lying in a vertical plane cutting the upper hull board, and said boards affording between them a free 45 clearance space through which pieces of refuse may be knocked by the saws.

4. In a machine of the class described, in combination with a saw cylinder, a pair of inclined hull boards located one above the 50 other and controlling the size of the openings past said saw cylinder, the upper hull board being located a farther distance from the saw cylinder than the lower hull board, and said hull boards affording between them 55 a free clearance space so positioned and disposed as to afford an uninterrupted horizontal passage from the saw cylinder between said boards, whereby pieces of refuse may be readily knocked by the saws through 60 said space and beyond the rear edge of the lower hull board.

5. In a machine of the class described, in combination with a saw cylinder, a pair of hull boards located one above the other and controlling the size of openings past said 65 saw cylinder, said hull boards affording a free clearance space between them and the lower hull board being of less width than the upper hull board, and its rear edge being lower than the front edge of the upper 70 hull board.

6. In a machine of the class described, in combination with a saw cylinder, a pair of hull boards located one above the other and controlling the size of openings past said 75 saw cylinder, said hull boards affording a free clearance space between them, the lower hull board being of less width than the upper hull board and having its rear edge located at a distance from the rear wall of the 80 casing and in a plane cutting the saw cylinder, and lower than the plane of the lower edge of the upper hull board.

7. In a machine for extracting and cleaning cotton, in combination with a rotary saw 85 cylinder, a pod-expeller and doffer-brush co-operating therewith, a pair of connected hull boards located one above the other and affording a free clearance space between them, said hull boards being pivotally 90 mounted in the casing, and means for simultaneously adjusting said hull boards on their pivot to vary the distance between their respective edges and the surface of said saw cylinder.

8. In a machine of the class described, in combination with a saw-cylinder, a plurality of superposed, separated hull-boards positioned to permit the passage between them of pieces of refuse knocked outward by the 100 saws, and controlling at their front edges the size of openings past the saw-cylinder, the bottom hull-board having its rear edge located at such a distance from the saw-cylinder as to permit the pieces of refuse thrown 105 outward by the saws to fall thereover.

9. In a machine of the class described, in combination with a saw cylinder, a plurality of superposed, separated hull-boards controlling at their front edges the size of openings past the saw cylinder, the bottom hull-board being of less width than the top hull-board and having its rear edge lying in a lower plane than the front edge of the top hull-board.

In testimony whereof, I have hereunto set my hand in presence of two subscribing witnesses.

JOHN E. MITCHELL.
